The ornamental design for a LED lamp, as shown and described.

DESCRIPTION

FIG. 1 is a front perspective view of a LED lamp showing our design;

FIG. 2 is a front view of the LED lamp of FIG. 1;

FIG. 3 is a rear view of the LED lamp of FIG. 1;

FIG. 4 is a left side view of the LED lamp of FIG. 1;

FIG. 5 is a right side view of the LED lamp of FIG. 1;

FIG. 6 is a top view of the LED lamp of FIG. 1;

FIG. 7 is a bottom view of the LED lamp of FIG. 1;

FIG. 8 is a front perspective view of the LED lamp of FIG. 1 shown in use with the light emitting part in diagonal line, the light being refracted by the prism; and,

FIG. 9 is a front perspective cross-sectional view of the LED lamp of FIG. 1.

The broken lines shown in the drawings illustrating environmental structures form no part of the claimed design.
